UNITED STATES PATENT OFFICE.

HIRAM STEVENS MAXIM, OF STREATHAM, LONDON, ENGLAND, ASSIGNOR TO VICKERS LIMITED, OF WESTMINSTER, ENGLAND.

BOMB FOR USE WITH AEROPLANES AND OTHER FLYING-MACHINES.

1,078,298.

Specification of Letters Patent. Patented Nov. 11, 1913.

Original application filed March 25, 1912, Serial No. 626,002. Divided and this application filed July 14, 1913. Serial No. 778,852.

To all whom it may concern:

Be it known that I, HIRAM STEVENS MAXIM, a subject of the King of Great Britain, residing at 382 High road, "Sandhurst Lodge," Streatham, in the county of London, England, formerly of "Ryecotes," Dulwich Common, in the county of London aforesaid, have invented certain new and useful Improvements in or Relating to 10 Bombs for Use with Aeroplanes and other Flying-Machines, of which the following is a specification.

This invention relates to bombs applicable for use with aeroplanes or flying machines or balloons and particularly to bombs of the character in which a detonating charge is retained in a position remote from the main charge until the bomb is discharged or released.

20 In connection with the use of bombs it is essential for effective working that the explosion take place so as to afford the highest degree of destruction whether of life or property, as earth works, forts or other 25 erections. It is therefore desirable that some amount of control be possible with regard to the bomb.

According to this invention the bomb is adapted to be exploded at a predetermined 30 or approximately predetermined distance from the ground, object or target by the initial impact of the bomb and, in order to accomplish the objects aimed at, the bomb is provided with a device constructed in such 35 a manner as to raise the bomb a certain distance after the same has struck the ground, object or target and prior to the firing of the main charge which is arranged to take place in the most favorable position for performing effective work.

In carrying out the invention the initial impact of the bomb causes the explosion of a predetermined charge of black powder or similar explosive whereby the bomb is 45 caused to rebound from the ground, object or target prior to the explosion of the detonating and main charges at a predetermined distance above or from the ground, object or target. The distance from the 50 ground, object or target at which the explosion of the main charge will take place will depend upon the strength of the explosive charge or the like whereby the rebounding of the bomb is effected after it has struck the

ground, object or target. The shell or casing of the bomb may, in the usual manner, be formed or provided with grooves; a loading of metal fragments or balls or the like, having the interstices between the same filled with a high explosive may also be provided, so that, as a result of the explosion, destructive fragments or bodies are disseminated or spread in all directions with the effect that the desired destruction is produced in regard both to life and buildings or erections.

In order that the said invention may be clearly understood and readily carried into effect I will proceed to describe the same with reference to the accompanying drawings in which—

Figure 1 represents a view in longitudinal section of a form of the improved bomb adapted for operation by rebound after striking the ground, object or target; and Fig. 2 is a view of the tail of the bomb showing a parachute applied thereto.

The bomb comprises a main casing *a* which may be provided with circumferential and longitudinal grooves or depressions so as to insure the casing or shell breaking into fragments when the bomb is exploded. The shell or casing is provided with an internal hollow member *a*² which extends beyond the casing or shell to form a tail piece *a*³. The tubular extension or tail piece *a*³ contains the auxiliary or detonating charge *a*⁹. The casing or shell *a* is provided at its forward end with a chamber *f* containing a charge of black powder or similar explosive. The forward end of the bomb is provided with a firing pin *c*⁵ which is held in the inoperative position by means of a shearing pin *f*⁷ so that when the bomb is liberated from the framing *b* of the aeroplane or flying machine by withdrawing the bolt *b*¹ incidental to the deflection of the lever *b*² the pendent arms or members *f*⁶ *f*⁸ admit of the release of the bomb; the firing pin *c*⁵ and the detonating charge *a*⁹ being thereupon rendered free to assume their position for firing and exploding their respective charges. The bolt *b*¹ works through saddle pieces *b*⁴ on the framing *b* and is adapted to engage with lugs *b*⁵ carried by the shell or casing *a* of the bomb. When the bomb strikes the ground, object or target the pin *f*⁷ which secures the firing pin *c*⁵ will be sheared and the firing pin will strike

the detonator c^8 causing the ignition of a fuse mixture contained in the passage c^9 . This passage communicates with a chamber f^2 through the openings f^3 , which are arranged transversely of the passage c^9 and serve to place the latter in communication with the chamber f^2 containing black powder. This chamber f^2 is placed in communication with another chamber f containing the main charge of black powder by way of the openings f^4 . The openings f^4 are formed in the walls of the chamber f^2 and are consequently arranged around the firing pin c^5 . The ignition of the black powder will cause the bomb to be blown or raised a distance from or above the ground, object or target, dependent on the strength thereof, and the fuse mixture in the passage c^9 is so arranged that it is adapted to reach and fire the auxiliary or detonating charge after this movement is effected.

The bomb may be secured to the flying machine or the like by the device hereinbefore described and the detonating charge a^9 and the firing pin c^5 may be retained in the inoperative position by the arms or members f^5 depending from the framing b of the machine. Suitable vanes or blades f^6 are disposed at the tail of the bomb and serve to direct the bomb in its movement. These blades may, however, be replaced by a suitable parachute arrangement d , Fig. 2, whereof the members d' are adapted, upon the release of the bomb, to extend in a manner similar to an umbrella so as to constitute the parachute. The members d' of the parachute are pivoted at d^2 to the tail piece a^3 of the bomb and are provided with projections d^4 which, when the parachute is closed, are adapted to enter the openings d^5 in the tail piece a^3 and retain the detonating charge a^9 in the inoperative position.

It will be seen that the bomb comprises a main charge of high explosive adapted for being fired or exploded by means of an auxiliary charge a^9 capable of passing from the rear to the fore end of the apparatus and that the firing is dependent upon the initial impact of the bomb causing the ignition or explosion of a predetermined charge

of black powder or similar explosive, whereby the bomb is caused to rebound; the explosion of the detonating and main charges taking place while the bomb is elevated or situated at a predetermined distance above 55 or from the ground, object or target.

What I claim and desire to secure by Letters Patent of the United States is:—

1. In a bomb for use with aeroplanes or flying machines, the combination of a main charge of high explosive, a detonating charge, and a charge of black powder which is fired by the initial impact of the bomb so as to cause the detonating and main charges to be exploded at a predetermined 60 distance above or from the ground, object or target.

2. In a bomb for use with aeroplanes or flying machines, the combination of a main charge of high explosive, a detonating 70 charge capable of moving relatively to the main charge, a parachute for retarding the motion of the bomb during its descent and a charge of black powder which is fired by the initial impact of the bomb so as to cause 75 the same to rebound and the detonating and main charges to be exploded at a predetermined distance above or from the ground, object or target.

3. In a bomb for use with aeroplanes or 80 flying machines, the combination of a main charge of high explosive, a detonating charge capable of moving relatively to the main charge, a parachute which becomes operative when the bomb is released and which 85 is adapted to retain the detonating charge in the inoperative position until such release is effected, and a charge of black powder which is fired by the initial impact of the bomb so as to cause the same to rebound 90 and the detonating and main charges to be exploded at a predetermined distance above or from the ground, object or target.

In testimony whereof I affix my signature in presence of two witnesses.

HIRAM STEVENS MAXIM.
